(54) **BOILERS, STEAM,STONE COAL FOR**

(76) Inventor: **James G. Wilson**

James G. Wilson, a Citizen of the United States.
- Sellers Patent

Dated February 22^d 1838.

The Schedule referred to in these Sellers Patent & making part of the same,
containing a description in the words of the said James G. Wilson himself of
his improvement in Steam Boilers for using stone coal.

Set a boiler or tank of suitable materials for carrying Steam & heat the boiler
is divided into three sections, the two sections lay on a horizontal plane parallel to each
other, and at a sufficient distance apart to admit the coal, let the other section lay
horizontally, but directly over the other two, presenting the salient angle of a triangle
at a sufficient distance to admit the coal, these sections may be of a round square
or angular form, at the ends of each section there are openings so as to give a free com-
munication of water from one to the other, On one or both sides of the boiler may
be doors fastened to the upper sections so as to open & admit fuel between the upper
& lower sections, these doors are divided so as to feed the fire at different times, & when
such they are intended to confine the heat within the body of water, Under the boiler
a s. clevis is a rate to lay the coal on, underneath the grate is a shaft with pins on it
which revolves by having one or both ends attached to the machinery & when in op-
eration the shaft by increasing or diminishing the velocity of its revolution will grad-
ually heat.

That I claim as my invention is the arrangement of the boiler the principle
of spreading the coal between the length of the sections of the boiler and feeding the fire
in sections, and the principle of creating a draft by shafts & pins, & the use to which
this improvement is applied to. Dated 25^d January 1838.
